UNITED STATES PATENT OFFICE.

FRED R. JOHNSON, OF ARLINGTON, MASSACHUSETTS, ASSIGNOR TO HUFF ELECTROSTATIC SEPARATOR COMPANY, OF ARLINGTON, MASSACHUSETTS, A CORPORATION OF MAINE.

ELECTROSTATIC SEPARATION.

Application filed May 17, 1924. Serial No. 714,004.

To all whom it may concern:

Be it known that I, FRED R. JOHNSON, a citizen of the United States of America, and resident of Arlington, in the county 5 of Middlesex and State of Massachusetts, have invented new and useful Improvements in Electrostatic Separation, of which the following is a specification.

This invention relates to electrostatic separation of unlike particles from a comminuted mass of materials having different characteristics by subjecting the particles to an electrostatic charging influence and then moving the particles past an electrode 10 adapted to deflect the different particles different amounts; and the invention is particularly useful in that method of separation wherein the particles are charged by a spray electrode as they approach the separating electrode, the particles being supported upon a conducting surface adapted 15 to conduct away a part or all of the charges from the particles having greater conductivity.

20 A principal object of the invention is to separate relative large pieces of material such as coke from clinkers where the pieces may be an inch in diameter or larger. However, the invention is applicable to a wide variety of materials, a few typical uses comprising the separation of iron from zinc, iron from sand, rock and quartz from fluorspar and felspar, mica from garnet and quartz, 25 quartz from garnet, roots from gum, shale from rock-salt, alumina from aluminum, aluminum from gross, abrasives and other electric furnace products, etc. etc. Other objects are to separate the unlike materials more completely, to reduce the number of 30 stages of separation, to maintain a high density separating field without disruptive discharges, to facilitate the adjustment and operation of the separators, to increase the life of the separating electrodes, and generally to improve the art of electrostatic separation.

35 For the purpose of illustrating the genus of the invention certain concrete embodiments are shown in the accompanying drawings in which—

40 Fig. 1 is a front elevation of a complete machine;

45 Fig. 2 is a side elevation of the machine;

50 Fig. 3 is a vertical longitudinal section of Fig. 1;

55 Fig. 4 is an enlarged detailed section corresponding to Fig. 3;

60 Fig. 5 is a longitudinal section of one of the separating electrodes and its support;

65 Fig. 6 is a plan view of the separating and spraying electrodes;

70 Fig. 7 is a circuit diagram showing one type of circuit connections;

75 Figs. 8 and 9 are transverse and longitudinal sections of a modified separating electrode;

80 Figs. 10 and 11 are similar views of a further modification;

85 Figs. 12 and 13 are similar views of still another modification; and

90 Fig. 14 is a section on line 14—14 of Fig. 13.

95 The particular embodiment of the invention chosen for the purpose of illustration 75 comprises upright frame members 1, a hopper 2 mounted at the top of the frame, a feed roller 3 for delivering material from the hopper at approximately uniform rate, a series of inclined shelves 4 for directing the material along a zig-zag path of the separating electrodes successively, rollers 5 over which the material passes as it leaves the shelves 4, spray electrodes 6 for charging the particles as they pass over the 80 rollers 5, separating electrodes 7 arranged in vertically staggered relationship for separating the materials as they fall from the ledges constituted by rollers 5, and hoppers 8 for receiving one class of the unlike particles, the inclines 9 deflecting the other class of particles to the sides of the machine. The feed roller 3 is mounted directly on the drive shaft which is driven by pulley 10 and the rollers 5 are geared together to rotate in unison by means of the train of gears shown in Fig. 2. The separating electrodes are driven by belts 11 which pass over pulleys driven by the aforesaid train of gears.

100 The inclined shelves 4 are pivotally supported on the end uprights 16 by means of depending ears 12 and vertically adjustable brackets 12' (Fig. 4), the shelves being agitated by means of vertically reciprocating rods 13 carrying arms 14 upon which 105 the shelves rest near the side opposite to

the ears 12. The rods 13 are guided by brackets 15 secured to the end uprights 16 and pass through openings 17 near the opposite ends of the shelves. The rods 13 are oscillated vertically by means of toothed wheels 18 upon which the rods rest (Fig. 3).

Referring to Figs. 4, 5 and 6 each of the separating electrodes 7 comprises two heads 19 and 20, which are preferably formed of wood or other insulating material, journaled through ball bearings in brackets 21, which are adjustably mounted by means of thumb screws 22 in the uprights 1, a cylinder 23, also of wood or other insulating material, interconnecting the heads 19 and 20, a plurality of tubes 24 extending between the heads inside the cylinder 23, and a rod 25 extending axially through head 19, the inner end of the rod being electrically connected to the tubes 24 and the outer end carrying a loose ring 26 which is connected to the conductor 27. The pulley 28 is mounted on the projecting end of head 20. The electrodes 7 are braced by adjustable arms 33 (Fig. 4). The spray electrodes 6 each comprises two metallic strips 29 mounted in spaced parallel relationship in grooves in cross-bar 30 which is mounted on swinging arms 31 adjustably mounted on the uprights 1 by means of thumb nuts 32.

The circuit arrangement shown in Fig. 7 includes a mechanical rectifier 35 connected on one side through resistance 36 to the spray electrodes 6 and at the other side to the rollers 5; and a transformer 37 connected through a vacuum rectifier 38 to the electrodes 7 and through a conductor 39 to the rollers 5. The positive sides of the two circuits are connected to the rollers 5 and the negative sides respectively to the electrodes 6 and 7 although the connections may be reversed for certain classes of work. By employing two separate circuits the electrodes 6 and 7 may be charged to different potentials and may be excited at different frequencies of pulsation. For example, in separating coke from clinkers markedly superior results may be attained by charging the spray electrodes 6 at a potential of approximately 20,000 volts and 125 cycles frequency and the separating electrodes 7 at a potential of approximately 15,000 volts and 60 cycles frequency.

The electrode shown in Figs. 8 and 9 comprises a stationary axial support 41 mounted in fixed supports 42 and carrying a fixed eccentric contact member 43 intermediate its ends. Surrounding support 41 are two heads 44 and 45 interconnected by a cylindrical sleeve 46, each of these parts preferably being formed of wood or other insulating material. Conducting bars 47 extend between the heads 44 and 45 inside the sleeve 46 and are supported at their opposite ends by be-

ing set into recesses in heads 44 and 45 insulating strips 47^a being mounted between the bars 47. The rotor formed by heads 44 and 45, sleeve 46, and bars 47, is journaled upon rings 48—48' and 49—49' respectively fast upon the rotor and the axial support 41. The head 44 is preferably provided with an integral pulley 50 for revolving the rotor as described in connection with the electrodes 7. The eccentric contact element 43 contacts with the inner sides of the bars 47 as the bars pass through a predetermined arc of their rotation and conducts the exciting current thereto from the conductor 27' which corresponds to conductor 27 in Fig. 7.

The electrode shown in Figs. 10 ad 11 is similar to that shown in Figs. 8 and 9 except in that the conductor bars 47 are replaced by tubes 47'.

The electrode shown in Figs. 12, 13 and 14 is similar to that shown in Figs. 10 and 11 except in that the shaft 60 turns with the rotor and current is conducted to the tubular bars 47" through a stationary contactor 61, thence through commutator bars 62 mounted in shaft 61 (which is formed of insulation material) and thence through conductors 63 extending radially from the commutator bars to the tubular bars 47" respectively.

The rate of rotation of the static electrodes may be slow or fast but for separating larger particles such as coke from clinkers the rotation is preferably slow, e. g. no faster than is necessary to relieve the static stresses in the cylindrical shield 23 or 46 before dielectric break-down as hereinafter described. Inasmuch as the electrodes 7 are formed of circumferentially spaced bars the distribution of flux between these electrodes and the rolls 5, where the field is of course most concentrated, is varied as the bars move past this region. Moreover the area of the shield (23 or 46) which is subjected to the greatest dielectric stresses is continually shifted as succeeding sections of the shield move into opposition to the roll 5, thereby relieving the stresses after a brief interval and permitting the use of a much higher field density without destroying the dielectric quality of the shield.

This invention, which is the result of long experience and extensive experimentation, makes it possible to separate coke from clinkers (and other large pieces) up to one inch in diameter and higher, whereas it has not been possible heretofore, so far as I am aware, electrostatically to separate particles larger than approximately one-quarter inch. Thus the invention broadens the art of electrostatic separation to include many new fields heretofore excluded because of size restrictions and particularly it makes the separation of coke from clinkers commercially feasible.

Salient features of the invention consist in periodically varying the distribution of the static field (which is effected by rotation of the electrode 7 in the illustrative embodiment), and in pulsating the spray discharge or the static field, whereby large pieces of material, such as coke and clinkers, may be separated.

I claim:

10 1. The art of electrostatic separation of unlike particles from a comminuted mass of materials having different characteristics which comprises moving the material over a charged surface through a spray discharge

15 of opposite polarity and thence through a static field of said opposite polarity and periodically varying the intensity of said static field.

2. The art of electrostatic separation of unlike particles from a comminuted mass of materials having different characteristics which comprises moving the material over a charged surface through a spray discharge of opposite polarity and thence through a static field of said opposite polarity, rapidly varying the intensity of said static field, and slowly varying its distribution in the path of the material.

3. The art of electrostatic separation of unlike particles from a comminuted mass of materials having different characteristics which comprises moving the material over a charged surface through a pulsating spray discharge of opposite polarity and thence through a static field of said opposite polarity.

4. The art of electrostatic separation of unlike particles from a comminuted mass of materials having different characteristics which comprises moving the material over a charged surface through a pulsating spray discharge of opposite polarity and thence through a pulsating static field of said opposite polarity.

45 5. The art of electrostatic separation of unlike particles from a comminuted mass of materials having different characteristics which comprises moving the material over a charged surface through a pulsating spray discharge of opposite polarity and thence through a static field of said opposite polarity, and continually varying the distribution of said static field.

6. The art of electrostatic separation of unlike particles from a comminuted mass of materials having different characteristics which comprises moving the material over a charged surface through a pulsating spray discharge of opposite polarity and thence through a pulsating static field of said opposite polarity, and continually varying the distribution of said static field.

7. The art of electrostatic separation of unlike particles from a comminuted mass of materials having different characteristics

which comprises moving the material over a charged surface through a spray discharge of high potential and thence through a pulsating static field of lower potential.

8. The art of electrostatic separation of unlike particles from a comminuted mass of materials having different characteristics which comprises moving the material over a charged surface through a pulsating spray discharge and thence through a pulsating static field of lower frequency.

9. The art of electrostatic separation of unlike particles from a comminuted mass of materials having different characteristics which comprises moving the material over a charged surface through a pulsating spray discharge of high potential and thence through a pulsating static field of lower frequency and lower potential.

10. The art of electrostatic separation of unlike particles from a comminuted mass of materials having different characteristics which comprises moving the material over a charged surface through a pulsating spray discharge of high potential, thence through a pulsating static field of lower frequency and lower potential, and continually varying the distribution of the static field in the path of the material.

11. An electrostatic separator comprising means for feeding comminuted material over a conducting surface, means for directing a pulsating spray discharge to the material on said surface, means for subsequently subjecting the material to a pulsating static field of lower frequency and lower potential, and means for continually varying the distribution of the static field in the path of the material.

12. An electrostatic separator comprising means for feeding comminuted material over a conducting surface, means including one circuit for directing a pulsating spray discharge to the material on said surface, and means including another circuit for subsequently subjecting the material to a pulsating static field of lower frequency and lower potential.

13. An electrostatic separator comprising a static electrode, a shield for the electrode, means for directing charged particles into the shielded influence of said electrode, and means for continually changing the electric stress in the shield.

14. An electrostatic separator comprising a static electrode, a shield for the electrode, means for directing charged particles into the shielded influence of said electrode, and means for continually moving one of said first two elements to relieve the electric stress in the shield.

15. An electrostatic separator comprising a static electrode, a shield for the electrode, means for directing charged particles into the shielded influence of said electrode,

- means for rendering the field more intense on the side of the electrode adjacent the path of the particles, and means for continually shifting the shield to bring different parts into operative position. 40
16. An electrostatic separator comprising a static electrode, a shield surrounding the electrode, means for directing charged particles past the electrode, and means for rotating the shield to bring different sections 10 between the electrode and particles. 45
17. An electrostatic separator comprising a static electrode, a shield surrounding the electrode, a charged surface for directing 15 particles past the electrode, and means for rotating the shield to bring different sections between the electrode and particles. 50
18. An electrostatic separator comprising a static electrode, a shield surrounding the 20 electrode, means for directing particles past the electrode, means for directing a spray discharge to the particles as they approach said electrode, and means for rotating the shield to bring different sections between 25 the electrode and particles. 55
19. An electrostatic separator comprising a static electrode, a shield surrounding the electrode, and means for mounting the shield to turn about an axis passing therethrough. 60
- 30 20. An electrostatic separator comprising a static electrode, a cylindrical shield surrounding the electrode and means for mounting the shield to revolve about its axis. 70
- 35 21. An electrostatic separator comprising a static electrode, a shield surrounding the electrode, and means for rotatably mounting the electrode and shield. 75
22. An electrostatic separator comprising a static electrode, a shield surrounding the
- electrode, and means for rotatably mounting the electrode and shield to turn about the axis of the shield. 40
23. An electrostatic separator comprising a cylindrical sleeve and an electrode in the form of a plurality of spaced conductors 45 extending longitudinally of the shield inside thereof. 50
24. An electrostatic separator comprising a ledge, means for feeding comminuted material over the ledge, an elongate electrode extending along said ledge in opposition thereto, a shield surrounding the electrode, and a spray electrode opposed to said ledge immediately above said electrode. 55
25. An electrostatic separator comprising a plurality of electrodes arranged in vertically staggered relationship, superposed shelves for delivering comminuted material to the electrodes respectively, alternate shelves being inclined in opposite directions, 60 actuating means bridging the spaces between the superposed shelves, and means common to the respective shelves, for oscillating said actuating means. 65
26. An electrostatic separator comprising a plurality of electrodes arranged in vertically staggered relationship, superposed shelves for delivering comminuted material to the electrodes respectively, alternate shelves being inclined in opposite directions, 70 a vertically reciprocating rod for agitating said shelves, and a rotary toothed member upon which said rod rests whereby rotation of said member oscillates said shelves. 75

Signed by me at Boston, Massachusetts, this 6th day of May, 1924.

FRED R. JOHNSON.
